UNITED STATES PATENT OFFICE.

CHARLES E. BENTLEY, OF NEW YORK, N. Y.

PERFORATING-MACHINE.

SPECIFICATION forming part of Letters Patent No. 249,291, dated November 8, 1881.

Application filed March 10, 1881. (No model.)

To all whom it may concern:

Be it known that I, CHARLES E. BENTLEY, of the city, county, and State of New York, have invented a new and Improved Perforating-Machine, of which the following is a specification.

The object of this invention is to provide a simple, convenient, and rapidly-operating machine for making patterns for embroidery stamping.

Figure 1 is a side elevation of the perforating-machine. Fig. 2 is a plan of the same. Fig. 3 is an enlarged sectional side elevation on line *y y*, Fig. 4, of the perpendicular tube, rod and needle, and actuating mechanism. Fig. 4 is an enlarged sectional front elevation of the same on line *x x*, Fig. 3. Fig. 5 is an enlarged sectional elevation, showing the joint of the device.

Similar letters of reference indicate corresponding parts.

In the drawings, A represents the standard, to the side of which is pivoted, near its foot, a vertically-swinging arm, A', to the free end of which is secured an end of the chain B', that connects it with the treadle B, and to which is also secured an end of the cord or chain C', that passes up over the segmental rocking sheave C², which is pivoted in the standard brace C³, and is secured in an end fastening or thimble, a, whose open socket a' is fitted over the wrist-pin b of the horizontal balance-wheel C, which is pivoted on the top of said standard A, so that by working the treadle B the wheel C is revolved.

On the opposite side of the standard A from the brace C³ are two laterally-projecting lugs, c, in and between which is pivoted by bolts or pins d, so that it may swing in a horizontal plane, the frame D, provided with two forward-extending horizontal parallel ears, f, set a short distance apart, one above the other, and in the extremities of the ears f is pivoted an upright T-shaped spindle, E. A rocking-bar, F, provided with dependent end lugs, g, is pivoted on the horizontal head of said spindle E and parallel therewith by pins h, that are entered through said lugs g into the ends of said spindle-head E, so that said bar F and its attachments have, when in operation, the rotary motion of the spindle E and the up-and-down

rocking motion of the bar F. The spindle E and bar F constitute the gimbal-joint, connecting the horizontal arm G with the standard A. Held on the top of this bar F and at right angles thereto by a clamp, F', is the swinging arm G, the rear end of which is connected by a spiral spring, h', with the lower ear, f, of the frame D, by the tension of which spring h' said arm G and its attachments are moved in a vertical plane. To the outer end of this arm G is rigidly attached a perpendicular tube, H, surmounted by and interiorly communicating with a cylindrical shell, I, which is fixed at the junction of said arm G and tube H. Through opposite sides of this cylinder I are introduced sharp-pointed screws I', between which is held the crank-shaft K within said cylinder I. On the wrist-pin of said crank-shaft K is secured the upper end of a rod, L, that projects downward through the tube H, and has secured to its lower end by a pin, i, a stouter rod, M, whose lower end is screw-tapped, as shown at l, Fig. 3, and has screwed into it a short rod, N, in a longitudinal groove, m, in which a perforating-needle, O, is soldered. This groove m is of sufficient depth to receive the whole diameter of the needle O, which is soldered and fitted in it, so that the rod N will move freely up and down in the bushing P.

A bushing, P, is screwed into the lower end of the tube H, and through this bushing P the rod M is extended, and is thereby prevented from moving out of a vertical plane.

A sheave, Q, is keyed on the crank-shaft K for receiving the belt or cord Q', that is also passed through the cylinder I and around the counter-sheave R.

Centrally and vertically on the arm G is fixed a yoke, S, through the top of which is screwed a set-screw, n, whose point serves as the top bearing of the spindle S', that has its lower end pivoting in a bearing, o, on the top of the clamp F'. On this spindle S' are keyed in a horizontal plane the counter-sheave R and the smaller sheave R².

A belt or cord, T, connects the driving or balance wheel C with the sheave R², so that when said driving-wheel C is put in motion the crank-shaft K is rapidly revolved, with the effect of giving a quick up-and-down reciprocating motion to the rods L M N and needle O,

whereby, as the said needle O is passed over the surface of paper or other suitable material, the desired perforations are made.

A lug, p, extends laterally from the tube H, 5 near the bottom thereof, and has passed up through it a screw-threaded bolt or guide, V, having a convex head, s. It is designed to adjust this guide V in such a manner that its head s shall rest on the paper that is being perforated at a sufficient height above the point of the needle O to permit the latter to perforate to a sufficient depth.

The machine being set in motion, the operator takes hold of the guide V, and thus guides 15 the needle O over the lines or patterns drawn upon the paper, so that a perforated pattern or design is quickly formed.

It will be observed that the needle O is held rigidly perpendicular, so that none of the 20 perforations produced by it are made in a slanting direction, and that the horizontal arm G and gimbal-joint E F allow free horizontal and vertical motion to said needle O.

Having thus fully described my invention, I claim as new and desire to secure by Letters 25 Patent—

1. The swinging arm G on bar F, connected at the rear by a spiral spring, h', with the frame D, and at the other end with tube H, in combination with a cylindrical shell, I, at the junction of said arm and tube, the screws I', and the crank-shaft K, carrying the rods L M N, with needle O, as shown and described. 30

2. The combination, with the swinging frame D, carrying spindle E, of the rocking bar F, 35 having lugs g pivoted on the head of said spindle by pins h, whereby the attachments of said bar may have its rocking motion and at the same time the rotary motion of the spindle, as described.

CHAS. E. BENTLEY.
